UNITED STATES PATENT OFFICE.

WALTON G. CHRISTIAN, OF HOUSTON, TEXAS.

SAMPLE-TAKING DEVICE.

1,379,170.

Specification of Letters Patent. Patented May 24, 1921.

Application filed May 19, 1919. Serial No. 298,061.

To all whom it may concern:

Be it known that I, WALTON G. CHRISTIAN, a citizen of the United States, residing at Houston, in the county of Harris and State 5 of Texas, have invented certain new and useful Improvements in a Sample-Taking Device, of which the following is a specification.

This invention relates to new and useful 10 improvements in a sample taking device.

One object of the invention is to provide a device of the character described, adapted to be used in drilling wells, particularly oil wells, and equipped with means whereby 15 samples of the formation being pierced, as drilling progresses, may be taken. In drilling for oil, or other minerals, it is desirable that samples or specimens of the formation being pierced be obtained by means of which 20 the presence or absence of oil or other minerals is indicated. It is difficult to obtain accurate samples, inasmuch as water is forced down into the bore to carry away the cuttings from the bit. This device has been 25 provided for obtaining a core or sample of the formation being pierced, which will be protected from the water and maintained in its natural state, until the device is withdrawn to the surface of the ground, for the 30 examination of the sample.

Another object of the invention is to provide a device of the character described, which is simple in construction and which may be cheaply and easily manufactured 35 and readily removed and replaced.

With the above and other objects in view, the invention has particular relation to certain novel features of construction, operation and arrangement of parts, an example 40 of which is given in this specification and illustrated in the accompanying drawings, wherein:

Figure 1, is a vertical sectional view of the device, and

Fig. 2, is a transverse sectional view, taken on the line 2—2 of Fig. 1.

Referring now more particularly to the drawings wherein like numerals of reference designate similar parts in each of the 50 figures, the numeral 1, refers to the drill stem which is adapted to be let down into the bore, and the lower end of which carries the bit 2, which is attached to said stem by means of the collar 3. In general contour, 55 the bit 2 is of the usual form of the fishtail bit, now in common use, but is constructed

somewhat larger than the ordinary fishtail bit, and has the central opening 4, bored therethrough. The bit also has the water passageways 5, 5, extending from the upper 60 end thereof downwardly, and discharging on opposite sides of the bit through which water is supplied from the drill stem to the cutting points of the bit to carry away the cuttings during the drilling process. The 65 lower end of the core barrel 6 is threaded into the upper end of the bit. This barrel is tubular in form and may be of any length desired, and is somewhat smaller in diameter than the drill stem. This barrel is arranged concentrically within the stem, and its upper end carries a coupling 7, formed with a valve seat 8 therein, having the central fluid passageway 9, which is controlled by the ball valve 10 which is dropped into 70 the drill stem from the top of the ground just before taking the core. Threaded in the upper end of the coupling 7, there is an upwardly flared nipple 11, which retains the ball valve 10 in place, and which is 75 provided with fluid ports 12.

In drilling, the cutting blades of the bit disintegrate the formation, and the cuttings are carried away by the water which is forced under pressure down through the 85 drill stem and passageways 5, 5, said water returning laden with said cuttings up through the bore around the stem to the surface of the ground. The water which enters the nipple 11 passes on through the 90 ports 12, and then down through the stem as explained. As drilling progresses, it is apparent that a core will be formed which will pass up through the opening 4, into the barrel 6, and as said core is advanced up 95 into the barrel, the ball valve 10 will lift to permit the air and water in the barrel to escape. When the stem is withdrawn to obtain the sample, the valve 10 will seat and close the seat 8, and the sample will be re- 100 tained in the barrel by air pressure from beneath, and when said valve is seated, the fluid in the stem above the nipple 11 will be permitted to pass through the ports 12, and on down and out through the passage- 105 ways 5.

What I claim is:

1. A device of the character described, including a hollow drill stem, a drill bit attached to the lower end thereof and provided with a central opening, a barrel whose lower end is attached to the upper end of

said bit, in alinement with said opening, said barrel extending up into the stem, a valve seat carried by the upper end of said barrel, an upwardly flared nipple threaded into 5 said seat, and a ball valve within said nipple, and coöperating with said seat.

2. A device of the character described, including a hollow drill stem, a drill bit attached to the lower end thereof, having a 10 central opening, a core barrel threaded into the upper end of said bit in alinement with said opening and extending up in through the stem, a valve seat carried by the upper

end of the barrel and provided with an opening, an upwardly flared nipple screwed 15 into said seat and provided with fluid ports, a ball adapted to be dropped within said nipple to form a valve for controlling the passageway through said seat.

In testimony whereof I have signed my 20 name to this specification in the presence of two subscribing witnesses.

WALTON G. CHRISTIAN.
